INVENTOR:

G. G. Thompson.

UNITED STATES PATENT OFFICE.

GILBERT G. THOMPSON, OF DES MOINES, IOWA.

PIPE-CUTTER.

SPECIFICATION forming part of Letters Patent No. 377,725, dated February 7, 1888.

Application filed November 1, 1886. Serial No. 217,683. (No model.)

To all whom it may concern:

Be it known that I, GILBERT G. THOMPSON, a citizen of the United States, residing at Des Moines, in the county of Polk and State of Iowa, have invented a certain new and useful Improvement in Hand Turning and Cutting Machines; and I hereby declare the following to be a full, clear, and exact description of my invention, such as will enable others skilled in the art to which it pertains to make and use it, reference being had to the accompanying drawings, which form a part of this specification.

My invention relates to hand turning-machines adapted to turn or cut cylindrical and round tapering metal shafts; and it consists in the peculiar features of construction and novel arrangement and combination of parts, herein-after fully described and claimed.

The object of the invention is to produce a light, durable, and portable hand-machine adapted to turn and cut off shafting and piping. I attain this by the mechanism illustrated in the accompanying drawings.

Figure 1 is a side elevation of my improved machine. Fig. 2 is a front elevation looking from the right of Fig. 1. Fig. 3 is a rear elevation looking from the left of Fig. 1. Fig. 4 is a vertical section. Figs. 5 and 6 are views of detail parts, and will be hereinafter referred to.

Similar letters refer to similar parts throughout all the several views.

A represents a chuck having recessed boxes or slots on opposite sides, as B B, holding two notched or guttered jaws, C C, adjustable for centering by the set-screws D D D D and the adjusting-screw E, the barrel of the chuck terminating at one end in a circular disk, F, which is perpendicular to the bore of the chuck. G is another and larger disk, with an arm or lever, H, having an opening, I, in the center corresponding to the opening or bore through the barrel of the chuck A. In the back of the disk G is a circular recess, J, in which is fitted the disk F of the chuck A, the disk F being held in the recess by the guide-clamps K K K, so that the disk F is free to revolve in the recess J and the disk G is free to rotate upon the disk F of the chuck A. On the face of the disk G and arm H are flanges or guides L L, which receive a sliding block or tool-holder, M, carrying an adjustable cutting-tool, N, held in place by a clamp-plate, O, and set-screws P P.

R is a small shaft having on one end a handle, S, and mounted in the lug T, which projects from the arm H. The shaft R is screwed 55 into the boss U of the tool-holder M, and by means of the handle S may be operated to feed the cutting-tool N in toward the center of the shaft or pipe operated upon, or to draw it out.

V is a collar rigidly attached to the shaft R. 60

W is a spiral toothed wheel rigidly secured to the shaft R, which, with the collar V, forms shoulders that prevent the shaft R from moving longitudinally in feeding the cutting-tool in or out.

X is a sleeve which runs loosely upon a stud, Y, and forms the handle grasped by the operator to rotate the arm H and disk G upon the chuck A. The sleeve X is provided with a worm-wheel, Z, made, preferably, integral therewith, which engages the toothed wheel W, and as the disk G, carrying the cutting-tool N, is being revolved by the operator (the sleeve X being firmly held in the hand) the worm-wheel Z automatically feeds the cutting-tool N toward the center of the pipe or shaft operated on. Upon one end of the stud Y, and rigidly secured upon it, is an eccentric-collar, a, one part of which is enlarged to form a shoulder, b. The eccentric a fits into a hole 65 in the end of the arm H and is held rigidly in place by a nut, c, which screws onto a thread cut on the end of the eccentric-collar a and draws the shoulder b tightly against the face of the arm H. When it is desired to adjust 85

the cutting-tool, by sliding the tool-holder M the nut c is loosened and the eccentric a turned half round, which moves the sleeve X, carrying the worm-wheel Z, outward from the toothed wheel W, as shown in Fig. 6, leaving the shaft 90 R free to be rotated by the handle S. When the adjustment has been made, the eccentric a is turned back again and the worm-wheel brought into mesh with the toothed wheel W and the nut c retightened. There is a groove 95 made in the sliding block M, into which the cutting-tool N is placed, the cutting-tool being held therein by a plate, O, secured by cap-screws to the sliding block.

When a pipe or shaft is to be turned by this machine, it is placed in the barrel of the chuck A, projecting through the opening I of the disk G, the jaws C C of the chuck being tightened by the set-screws D D D D and adjusting-screw

E and the cutting-tool adjusted by means of the shaft R and handle S. The disk G is then rotated upon the disk F of the chuck A by the arm or lever H and the handle X, carrying 5 the cutting-tool round the pipe or shaft to be operated upon, the cutting-tool being automatically fed to its work, in the manner hereinbefore described.

This machine may be employed for cutting 10 off piping or round bars of metal too large to be cut with a cold-chisel to advantage; but it is more especially adapted to turning up new shoulders on carriage axles or spindles that have worn until the boxing in the hub has too 15 much lateral play on the spindle.

Having thus described my invention, what I claim as new, and desire to secure by Letters Patent, is—

1. The combination of the chuck A, disk 20 F, oppositely - opposing jaws C, adjustably mounted in chuck A, rotatable arm H, having disk G, clamps K on the latter adapted to engage disk F, and a cutter mounted adjustably on arm H, substantially as set forth.
- 25 2. The combination of the chuck A, having recesses B, disk F, jaws C, received by said recesses B, set-screws for adjusting said jaws,

rotatable arm H, having disk G, clamps K on the latter adapted to engage disk F, and a cutter mounted adjustably on arm H, substantially as set forth. 30

3. The combination of the chuck having adjustable jaws, a rotatable arm having an enlargement perforated for the reception of the pipe, suitable means for securing said chuck 35 loosely to said arm, a cutter mounted in a sliding block, and a rod mounted on said rotatable arm adapted to adjust said cutter and its block, substantially as set forth.

4. The combination of a rotatable pipe-cutting device having an operating-arm, a cutter mounted thereon, a rod mounted loosely on said arm and suitably connected with said cutter, a toothed wheel mounted on said rod, and a rotatable handle at the end of said arm having a worm - wheel adapted to engage said toothed wheel and feed the cutter automatically forward as the arm is revolved, substantially as set forth. 40 45

GILBERT G. THOMPSON.
